A. MANIS

VALVE LOCK

Filed Sept. 4, 1924

INVENTOR

Adolph Manis
BY C. P. Gepel
his ATTORNEY

UNITED STATES PATENT OFFICE.

ADOLPH MANIS, OF BROOKLYN, NEW YORK.

VALVE LOCK.

Application filed September 4, 1924. Serial No. 735,766.

To all whom it may concern:

Be it known that I, ADOLPH MANIS, a citizen of the United States, and a resident of Brooklyn, county of Kings, and State of New York, have invented certain new and useful Improvements in a Valve Lock, of which the following is a specification.

This invention relates to an improved valve lock, and more particularly, in a preferred embodiment thereof, is designed for application and use in connection with motor driven vehicles whereby the flow or supply of fuel, such as gasoline, for the operation of the motor, may be prevented and the possibility of theft or operation of the vehicle by unauthorized persons, reduced to a minimum.

It is another object of my invention to provide a valve lock for the above purpose, which can be easily and quickly applied to the modern motor vehicle without necessitating any radical structural changes therein, and which, when applied, cannot be detached or removed from its operative position.

In a simple and practical embodiment of the device, a tumbler pin cylinder lock is associated with a rotary valve plug interposed in the fuel supply line, said lock having a key receiving barrel mounted for rotary and axial movement and said barrel and the valve plug being provided with co-acting means, whereby when the barrel is rotated to a predetermined position and then shifted axially, it is automatically connected with the valve plug whereby the latter may be moved to its open or closed positions.

With the above and other objects in view, the invention consists in the improved valve lock, and in the form, construction and relative arrangement of its several parts as will be hereinafter more fully described, illustrated in the accompanying drawing, and subsequently incorporated in the subjoined claims.

In the drawing wherein I have illustrated a simple and desirable construction and in which similar reference characters designate corresponding parts throughout the several views:

Figure 1 is a sectional view showing my

improved lock valve arranged in the fuel supply pipe of a motor vehicle;

Figure 2 is a sectional view taken on the line 2—2 of Figure 1;

Figure 3 is a view similar to Figure 1 showing the valve in open position;

Figure 4 is a plan view;

Figure 5 is a detail end elevation of the barrel of the cylinder lock; and

Figure 6 is a similar view of the rotary valve member.

Referring in detail to the drawing, where in I have shown the device mounted and arranged in operative position on the board B above the accelerator pedal of a motor vehicle, the valve body 5 which may be of any preferred form or shape, is provided with a flat upper surface 6 contacting closely against the underside of the floor board.

This valve body is provided with horizontally extending nipples 7 to which the respective sections 8 of the gasoline supply pipe are connected. In order to obtain an absolute fluid-tight connection between the pipe sections and the nipples 7, I provide each pipe section in spaced relation to its end with an annular flange or collar of V shape form in cross-section, said collar having the oppositely beveled surfaces 9. Each nipple 7 is provided with an internal shoulder 10 against which the end of one of the pipe sections 8 seats, while one of the beveled faces 9 of the collar on said pipe section seats against the chamfered or beveled surface 11 on the end of said nipple. The nipple 7 is exteriorly threaded to receive the internally threaded coupling member 12, one end of which is provided with an internal beveled face 13 for engagement with the other beveled face 9 of the collar on the pipe section 8. Thus it will be apparent that when the coupling member 12 is screwed up tightly upon the nipple 7 so as to frictionally engage the beveled faces of the collar with the beveled surfaces of the coupling member and the nipple 7, a fluid-tight connection is secured.

The valve body 5 is formed with a longitudinally extending fluid passage or bore 14 which is intersected centrally of the valve body by the chamber 15 which receives the

- rotary valve plug or member 16, said valve member having a port 17 extending transversely therethrough in the plane of the passage 14.
- 5 The valve chamber 15 at one of its ends opens into a recess 6' formed in the upper face 6 of the valve body. A cylinder lock of the Yale type is associated with the valve body 5, the cylinder 18 of the lock being 10 fixed within an outer shell or sleeve 19 extending through the opening bored through the floor board B. A face plate 20 is arranged over the upper surface of the floor board and is provided with an opening 15 therein through which the end of the lock cylinder 18 projects. The lower end of said sleeve and the cylinder 18 is engaged through an opening in a plate 21, the end of the sleeve 19 being formed with an outwardly projecting beveled flange 22 to coact with a beveled face formed on the plate 21 at one side of the opening therein. This plate is engaged in the recess 18 of the valve body and permanently fixed thereto by 25 means of a plurality of driving screws, indicated at 23. The other or upper end of the lock cylinder 18 has an out-turned flange 24 formed thereon extending within the plane of the face plate 20.
- 30 The cylinder 18 is formed with the usual eccentrically located opening 25 therethrough, to receive the barrel 26, said barrel being provided with the customary slot to receive the key 27. This barrel and the 35 lock cylinder are likewise provided with the usual spring-pressed sectional tumbler pins 28 with which the key 27 co-operates.
- As herein shown, the barrel receiving opening 25 at the upper end of the lock 40 cylinder is diametrically enlarged as at 29 to movably receive an annular flange 30 on the end of the barrel and which permits of the axial or longitudinal movement of said barrel relative to the cylinder. The wall of 45 the barrel is provided with a U-shaped slot 30 therein having circumferentially extending arms at its upper and lower ends. A pin 32 fixed in the cylinder 18 projects into this U-shaped slot and limits the rotary and 50 longitudinal movements of said barrel. At its lower end the barrel 26 is formed with a diametrically extending rib 33 which is adapted for engagement in a slot 34 formed in the upper end of the rotary valve member 16, as will be more fully hereinafter explained. This rib and the valve member 55 are also centrally provided with pockets or recesses to receive the opposite ends of a coil spring 35 which normally acts to yieldingly 60 hold the barrel in its normal position with the rib 33 thereof out of engagement in the slot 34. In such normal position, the rib 33 extends at a 90° angle with respect to the slot 34 and the port opening 17 in the valve 65 member is positioned at right angles to the fuel passage 14, thereby preventing the flow of fuel through said passage.
- In mounting the device in position on the board B, the cylinder lock which is rigidly fixed in position upon the body of the valve 70 by the plate 21 and screws 23, is inserted upwardly through the opening in the floor board, said plate and the upper surface 6 of the valve body engaging closely against the surface of said floor board. The valve body is provided with a plurality of threaded sockets at spaced points to receive the bolts or screws 36 which extend downwardly through openings in the face plate 20 and coinciding openings formed through the floor board. Thus the device is rigidly secured to the floor board. It will also be noted that it is impossible to detach the lock 75 from the valve by the removal of the screws 23, since the heads of these screws contact closely against the underside of the floor board.
- Having now described the several structural parts of my invention, the operation thereof will be understood as follows: 80
- In the normal position of the parts as shown in Figure 1, wherein the valve member 16 is in its closed position, the fuel cannot pass through the passage 14 of the valve body from the vacuum tank to the carburetor of the vehicle and it will be obvious that unless the proper key is inserted into the lock barrel 26, said valve member cannot be moved to its open position. Also, even if a key were inserted and the sectional tumblers properly positioned to permit rotation of the barrel member, one unfamiliar with the manner in which 85 said barrel must be operated, would in all probability, not be able to open the valve. In order to move the valve member to open position, after the key is inserted as shown in Figure 1, it is turned to rotate the lock barrel through 90°, said rotating movement being limited by the pin 32 engaging one side of the straight longitudinal portion of the slot 31 in the wall of said barrel. Such rotation of the lock barrel positions the rib 33 thereof in parallel relation 90 with the slot or recess 34 in the end of the valve member. The lock barrel is now forced inwardly against the action of spring 35 so that the rib 33 is engaged in the slot 34 and the rotation of the lock barrel then reversed, such movement being limited by engagement of the pin in the end of the upper horizontal portion of slot 31 in the wall of the lock barrel. In this latter reverse turning movement of said barrel, the valve member 16 is, of course, given a quarter turn so that the port 17 thereof is brought into alignment with the passage 14 through the valve body, thus permitting the uninterrupted flow of the fuel through said valve. In this inward axial movement of 100

the lock barrel 26, the sections of the tumbler pins 28 carried thereby are, of course, moved out of alignment with the tumbler pin sections in the cylinder 18 and, therefore, it will be apparent that the key 27 is locked in the barrel slot and cannot be withdrawn therefrom. This arrangement of the parts when the valve is open, is fully illustrated in Figure 3 of the drawings. It is, 10 of course, understood that when the owner of the vehicle desires to lock the valve in closed position, it is only necessary to reverse the above described operations and then withdraw the key 27.

15 From the foregoing description considered in connection with the accompanying drawing, the nature of my present improvements and the several advantages thereof in practical use will be fully understood. I have described the device as more especially designed for use in connection with the fuel supply pipe of a motor vehicle, but it will be manifest that my invention might also be advantageously applied to various other analogous uses. It will be seen that the several cooperating elements of my improved valve lock are few in number, simple in form, positive and reliable in their operation and not liable 25 to get out of order. The device may, therefore, be manufactured and sold at a nominal price. Since no radical alterations are necessary in the structure of the vehicle in order to properly apply a valve lock in 30 operative position, such application of the valve may be readily made by the individual vehicle owner. I have herein referred to the device as being applied to the floor board of the vehicle, but it will be understood that the same might also be otherwise located and connected in the fuel pipe supply line, as may be deemed most convenient.

I have herein described an embodiment 45 of the invention which in actual practice I have found gives excellent results. Nevertheless, it will be understood that the device is susceptible of embodiment in various other alternative structural forms and I, 50 therefore, reserve the privilege of resorting to all such legitimate changes in the form, proportion and relative arrangement of the detail parts, as may be fairly embodied within the spirit and scope of the 55 invention as claimed.

I claim:

1. In a device of the character described, the combination of a valve adapted to be interposed in a fuel conduit and having a movable valve member for controlling the flow of fuel through said conduit, a lock associated with said valve and including a key actuated member mounted for movement in two directions, said key actuated member 60 and the movable valve member having nor-

mally disengaged parts adapted to coact with each other when a proper key is engaged with said key-actuated member and predetermined movements imparted to said member to bring the key actuated member 70 into operating engagement with the valve member, whereby said valve member may be moved from closed to open position, or vice versa.

2. In a device of the character described, 75 the combination of a valve adapted to be interposed in a fuel conduit and having a movable valve member for controlling the flow of fuel through said conduit, a lock associated with said valve and including a key actuated member mounted for movement in two directions, said key actuated member and the movable valve member having normally disengaged parts adapted to coact 80 with each other when a proper key is engaged with said key-actuated member and predetermined movements imparted to said member to bring the key actuated member into operating engagement with the valve member, whereby said valve member may 85 be moved from closed to open position, or vice versa, and means normally locking the key-actuated member against movement and preventing the withdrawal of the key when 90 the valve is in open position.

3. In a device of the character described, 95 the combination of a valve adapted to be interposed in a fuel conduit and having a movable valve member controlling the flow of fuel through said conduit, a lock associated with said valve and including a key-actuated member provided with a key receiving slot and mounted for rotary and endwise movement, means normally locking said key-actuated member against movement, 100 said key-actuated member and the valve member having means adapted to co-operatively engage with each other when a proper key is inserted in said slot, and a predetermined rotary and endwise movement is imparted to said key-actuated member to bring the key actuated member into 105 operating engagement with the valve member, whereby the valve member may be moved from closed to open position, or vice versa.

4. In a device of the character described, 110 the combination of a valve adapted to be interposed in a fuel conduit and having a movable valve member controlling the flow of fuel through said conduit, a lock associated with said valve and including a key-actuated member provided with a key receiving slot and mounted for rotary and endwise movement, means normally locking said key-actuated member against movement, 115 said key-actuated member and the valve member having means adapted to co-operatively engage with each other when a proper key is inserted in said slot, and a predetermined 120

125

130

- 4
5. In a device of the character described, the combination of a valve adapted to be interposed in a fuel conduit and having a rotary valve member to control the flow of fuel through said conduit, a cylinder lock associated with said valve, a barrel rotatably mounted in the cylinder and also axially movable therein, said barrel having a key-receiving slot, tumbler pin sections mounted in the lock cylinder and barrel to normally lock said barrel against movement, said barrel and the valve member having complementary parts adapted to be brought into co-acting engagement when the proper key is inserted in said barrel and the barrel rotated and axially moved in said cylinder to bring the key actuated member into operating engagement with the valve member, whereby the valve member may be rotated from closed to open position, or vice versa.
6. In a device of the character described, the combination of a valve adapted to be interposed in a fuel conduit and having a rotary valve member to control the flow of fuel through said conduit, a cylinder lock associated with said valve, a barrel rotatably mounted in the cylinder and also axially movable therein, said barrel having a key-receiving slot, tumbler pin sections mounted in the lock cylinder and barrel to normally lock said barrel against movement, said barrel and the valve member having complementary parts adapted to be brought into co-acting engagement when the proper key is inserted in said barrel and the barrel rotated and axially moved in said cylinder to bring the key actuated member into operating engagement with the valve member, whereby the valve member may be rotated from closed to open position, or vice versa.
7. In a device of the character described, the combination of a valve adapted to be interposed in a fuel conduit and having a rotary valve member controlling the flow of fuel through said conduit, a cylinder lock associated with said valve and including a barrel mounted in the lock cylinder for rotary and axial movement, means for limiting such movements of the barrel, tumbler pin sections in the barrel and the lock cylinder normally locking said barrel against rotary or axial movement, said barrel having a key receiving slot, said rotary valve member and the lock barrel having complementary parts adapted to be brought into coacting engagement with each other upon the insertion of the proper key in said barrel, and imparting thereto the required rotational and axial movements, whereby the valve member may be rotated from closed to open position, or vice versa.
8. In a device of the character described, the combination of a valve adapted to be interposed in a fuel conduit and having a rotary valve member controlling the flow of fuel through said conduit, a cylinder lock associated with said valve and including a barrel mounted in the lock cylinder for rotary and axial movement, means for limiting such movements of the barrel, tumbler pin sections in the barrel and the lock cylinder normally locking said barrel against rotary or axial movement, said barrel having a key receiving slot, said rotary valve member and the lock barrel having complementary parts adapted to be brought into coacting engagement with each other upon the insertion of the proper key in said barrel, and imparting thereto the required rotational and axial movements, whereby the valve member may be rotated from closed to open position, or vice versa.
9. In a device of the character described, the combination of a valve adapted to be interposed in a fuel conduit and having a rotary valve member controlling the flow of fuel through said conduit, a cylinder lock associated with said valve and including a barrel mounted in the lock cylinder for rotary and axial movement, means for limiting such movements of the barrel, tumbler pin sections in the barrel and the lock cylinder normally locking said barrel against rotary or axial movement, said barrel having a key receiving slot, said rotary valve member and the lock barrel having complementary parts adapted to be brought into coacting engagement with each other upon the insertion of the proper key in said barrel, and imparting thereto the required rotational and axial movements, and thereafter the valve member may be rotated from closed to open position by means of the key in said barrel, or vice versa, the tumbler pin sections in said barrel being positioned out of alignment with the pin sections in the lock cylinder when the valve is in open position and coacting with the key to prevent withdrawal of the latter.
10. In a device of the character described, the combination of a valve adapted to be interposed in a fuel conduit and having a rotary valve member controlling the flow of fuel through said conduit, a cylinder lock associated with said valve and including a barrel mounted in the lock cylinder for rotary and axial movement, means for limit-

10. In a device of the character described, the combination of a valve adapted to be interposed in a fuel conduit and having a body and a valve member mounted therein controlling the flow of fuel through said conduit, a support against which one side of the valve body is engaged, a cylinder lock for said valve adapted to be secured to said valve and engaged through an opening 5 in said support, a plate bar securing said lock to the valve body having an opening therein through which one end of the cylinder lock is engaged, screws securing said plate to the side of the valve body engaged 10 against said support whereby the screw heads are covered by the support and access thereto prevented, a face plate surrounding the other end of the cylinder lock on the
- opposite side of the support, and screw bolts 20 passing through said face plate and the support and threaded in the valve body.
11. In combination with a valve including a rotatable valve member normally in closed position, a lock associated therewith including a lock member normally held in 25 locked position, said lock member and valve having normally disengaged parts adapted to connect the same for unitary rotation, and means to release said locking member and operable to connect said coacting parts 30 whereby the valve may be rotated to open position.

In testimony that I claim the foregoing as my invention, I have signed my name hereto.

ADOLPH MANIS.
